BOLUS GUN FOR CALVES

Orin H. Osborn, Le Sueur, Minn., assignor to
International Multifoods Corporation, Minneapolis,
Minn.

Filed Jan. 2, 1973, Ser. No. 320,472

Term of patent 14 years

Int. Cl. D24—02; D30—99
U.S. Cl. D83—12 A

FIG. 1

FIG. 2

FIG. 3

FIG. 1 is a view in perspective as seen from the front, top, and one side of a bolus gun for calves showing my new design;

FIG. 2 is a view in perspective as seen from the front, bottom, and the side opposite that shown in FIG. 1; and

FIG. 3 is a view in rear elevation thereof.

I claim:

The ornamental design for a bolus gun for calves, substantially as shown.
